United States Patent Office

Des. 211,484
Patented June 18, 1968

211,484

DRINK MIXER

Robert C. Le Sueur, River Forest, and Marlan H. Polhemus, Chicago, Ill., assignors to Scovill Manufacturing Company, Waterbury, Conn., a corporation of Connecticut

Filed Mar. 10, 1967, Ser. No. 6,171

Term of patent 14 years

(Cl. D44—1)

Fig. 1

Fig. 2

Fig. 3

Fig. 4

Fig. 5FIG. 1 is a perspective view of a drink mixer showing our new design, embodied in a single-spindle unit.

FIG. 2 is a top plan view thereof.

FIG. 3 is a front elevational view thereof.

FIG. 4 is a side elevational view thereof.

FIG. 5 is a perspective view of a drink mixer showing our new design, embodied in a triple-spindle unit.

The essential features of the design are shown in full lines.

We claim:

The ornamental design for a drink mixer, as shown and described.
